(57) **CLAIM**

The ornamental design for a mobile communications device, as shown and described.

DESCRIPTION

FIG. 1 is a perspective view of a mobile communications device showing my new design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a back view thereof; and

FIG. 8 is a second perspective view of the mobile communications device shown in FIG. 1, in which the mobile communications device is shown in an alternate position.

FIG. 9 is a third perspective view of the mobile communications device shown in FIG. 1, in which the mobile communications device is shown in an alternate position; and,

FIG. 10 is a fourth perspective view of the mobile communications device shown in FIG. 1, in which the mobile communications device is shown in an alternate position.

The broken lines are directed to visible environmental structure that is superimposed on claimed surfaces and that forms no part of the claimed design.
